UNITED STATES PATENT OFFICE.

LEONARD HUNTRESS DYER, OF WASHINGTON, DISTRICT OF COLUMBIA.

DESIGN FOR A FRAME FOR VEHICLES.

SPECIFICATION forming part of Design No. 29,772, dated December 6, 1898.

Application filed October 1, 1898. Serial No. 692,436. Term of patent 3½ years.

To all whom it may concern:

Be it known that I, LEONARD HUNTRESS DYER, a citizen of the United States, residing at Washington, in the District of Columbia, have invented and produced a new and original Design for Frames for Vehicles, of which the following is a specification, reference being had to the accompanying drawings, forming a part thereof.

Figure 1 is a plan view of the frame, showing my new design. Fig. 2 is a side view of the same.

As shown in the drawings, the leading and material features of my design consist of the parallel side members A A, curved at B and connected together by the cross members C D E at right angles with the side members

A A. The cross member C is connected to the side members at the beginning of the curved portion B.

F F are shorter members parallel to the side members A A, connecting the members C and D.

Having now described my invention, what I claim as new, and desire to secure by Letters Patent, is—

The design of a frame for vehicles as herein shown and described.

This specification signed and witnessed this 1st day of October, 1898.

LEONARD HUNTRESS DYER.
